UNITED STATES PATENT OFFICE.

ABRAM VAN BRUNT, OF NEW YORK, N. Y.

RAILWAY-FROG.

SPECIFICATION forming part of Letters Patent No. 634,780, dated October 10, 1899.

Application filed December 14, 1898. Serial No. 699,241. (No model.)

To all whom it may concern:

Be it known that I, ABRAM VAN BRUNT, of the city of New York, borough of Brooklyn, in the county of Kings and State of New York, have invented certain new and useful Improvements in Railway-Frogs, of which the following is a full, clear, and exact description.

This invention relates to an improvement in railway-frogs and crossings by which it is possible to prolong the life of the frogs and crossings indefinitely, the invention embodying certain peculiar features of construction by which the points of the frogs and crossings are rendered removable from the main portions, so that the points may be replaced when worn out. Ordinarily when the points of the frogs are broken the whole frog must be removed and a new one inserted, which operation involves much expense and inconvenience. My invention avoids this.

This specification is the disclosure of one form of my invention, while the claim defines the actual scope of the invention.

Reference is to be had to the accompanying drawings, forming a part of this specification, in which similar characters of reference indicate corresponding parts in all the views.

Figure 1 is a plan view of the invention applied to a railway-frog. Fig. 2 is an elevational view of the frog with parts broken out on the line 2 2 in Fig. 1. Fig. 3 is a section on the line 3 3 in Fig. 1. Fig. 4 illustrates the application of the invention to crossing-frogs.

Referring to the first three figures, the frog is constructed in the usual shape and has, therefore, the two side points 5 and 6 and the end points 7 and 8. In the frogs the end points 7 are not subjected to great usage, and consequently need not be replaced. The points 5, 6, and 8 are formed on movable sections 9 and 10 and are let into the surface of the main portion or body of the frog, so as to lie flush with the same. Now as the frog is used and these points are broken and chipped away by the action of the wheels of the cars the movable sections 9 and 10 may be lifted out of the frog and replaced. This involves an operation which will take very little time and will not, of course, be as expensive as re-

placing the entire frog. The removable sections 9 and 10 are formed with integral downwardly-projected studs 11, which project through openings in the upper side of the body of the frog, as shown best in Figs. 2 and 3, and which are threaded at their lower ends, so as to receive the nuts 12 by which to hold the several removable sections in place.

The body of the frog has its vertical walls provided on each side with openings 14, which expose the several nuts 12, thus permitting a tool to be inserted into the frog for the purpose of releasing the nuts. In the use of the frog therefore the frog is embedded in the street or road-bed in the usual manner, and to reach the studs 11 for the purpose of replacing the sections 9 and 10 it is only necessary to remove a small portion of the road-bed immediately adjacent to the openings 14, so that a wrench may be applied to the nuts 12.

The form of the invention shown in Fig. 4 does not differ materially from that shown in the other figures. It illustrates simply the application of the invention to a right-angled crossing. Here the crossing is provided with three removable sections 10^a, which are let into the body of the frog to lie flush with the upper face thereof. The sections 10^a have studs 11^a formed thereon, and these studs are similar in every respect to the studs 11 and are adapted to carry the nuts for the purpose of securing the sections 10^a in place.

Having thus fully described my invention, I claim as new and desire to secure by Letters Patent—

The combination of a railway-frog body having vertical side walls and having an opening in one of the same by which to reach the interior of the frog-body, and having cavities in its upper or top face, removable frog-points let into said cavities, studs formed on the frog-points and projecting downward through the top wall of the frog-body, and means for securing the studs against the under face of the top wall of the frog-body, substantially as described.

ABRAM VAN BRUNT.
